UNITED STATES PATENT OFFICE.

JAY H. WOOLHISER, OF ELMHURST, NEW YORK.

IMPLEMENT FOR CLEANING DRAINS.

1,215,461.

Specification of Letters Patent.

Patented Feb. 13, 1917.

Application filed November 20, 1915. Serial No. 62,642.

To all whom it may concern:

Be it known that I, JAY H. WOOLHISER, a citizen of the United States, and a resident of Elmhurst, in the county of Queens, city and State of New York, have invented new and useful Improvements in Implements for Cleaning Drains, of which the following is a specification.

This invention relates to improvements in implements for cleaning drain pipes, etc. of household plumbing fixtures, and has for its object to produce an implement of this kind which is adapted to be used without opening the traps or otherwise disconnecting any portion of the plumbing installation.

A further object of the invention is to provide an implement which may be effectively used by inexperienced persons, and which will with a few moments' manipulation, successfully clear out a clogged drain pipe sufficiently to allow the water to flow through it and carry the accumulated material into the sewer.

A further object of my invention is to produce a device of this kind which is of low manufacturing cost and embodies no working parts which may get out of order or necessitate repair.

With the above objects in view, my invention consists of the device shown in the accompanying drawings and hereinafter described and claimed.

In the said drawings,

Figure 1 shows my improved implement partially inserted in the U-trap of a wash basin; and

Fig. 2 is an enlarged view, partially in section, showing the construction of the implement.

My improved device consists essentially of a length of closely coiled steel wire 1, having at one end thereof a rigidly attached handle 2. The free end of the coil is bent to one side at an angle of about 45 degrees from the longitudinal line of the main portion of the coil as shown at 3, and is slightly pulled out to open the spaces between the adjacent turns of the coil as indicated at 4.

The main portion of the coil 1, which is preferably about a yard and a half in length, is coiled so tightly that the turns of the coil cannot be pulled apart by a person of ordinary strength. This result is attained by winding the coil around the mandrel with just sufficient relative longitudinal movement of the mandrel and the wire to pre-

vent the wire being coiled on itself. In other words, the turn in the wire is substantially a kink at right angles to the axis of the coil and is forced down against the tension of the wire into parallelism with the adjacent turn. By this construction the coil, while sufficiently flexible to follow the turns of the trap, is rigid enough to withstand considerable thrust before it will begin to "fold." Also, the close coiling, as described, prevents the adjacent turns of the wire in following the bends of the trap, from opening up sufficiently to catch against the edges of the connected pipes or other projections which may be encountered.

The handle 2 is preferably of the type known as a "screwdriver" handle; that is, one with which end thrust and rotation may be simultaneously imparted to the connected implement.

In using the device the "flexible rod" is thrust into the pipe to be cleaned by grinding it with one hand near the drain opening to feed it into the drain and at the same time 83 rotating the rod and thrusting it into the pipe with the other hand by means of the attached handle. The bent end of the coil with the opened turns serves the double capacity of a guide for causing the bend of the 85 implement to find its way around the turns of the pipe and of a hook to loosen the clogged material forming the obstruction and catch the lint or other refuse which may be pulled out of the pipe. The chief cause 90 of stopped drains is the accumulation of lint or other insoluble fibrous material against which the soap, grease, etc., is packed when the flow through the drain is impeded. The mass is soft enough for the 95 flexible rod to penetrate easily, but unless means are provided for the rod to take hold of the fibrous material, the obstruction will not be fully broken up even though it will allow the water to pass for a time. By opening the coils in the offset portion slightly, they will catch the threads or fibers so that the whole mass clogging the drain may be withdrawn with the implement. It is not necessary that the end of the opened-up coils 105 terminate in a point after the manner of a cork screw in order to penetrate this material, and such construction is not desirable, for the rod with the pointed end would penetrate the lead of the pipe. This may 110 be prevented by flattening together the two last turns of the offset portion as shown in

the drawing. In its action as a guide the bent end, by its simultaneous progressive and rotative movement, causes the rod to follow the turns of the pipe and pass any obstruction that may be encountered. For instance, in passing the plug 5 at the bottom of the U-trap 6, the end of the rod will engage the shoulder 7 should the bent portion be projecting downwardly when the end reaches that point, but the flexibility of the rod will allow it to "buckle" slightly with the continuous thrust until the rotation of the rod turns the bent portion upwardly clear of the shoulder. The rod will then pass easily through the trap as the coils are too close to catch even on the sharp edge of the plug opening.

In making a turn around an elbow the action is the same. The rod will "buckle" slightly until the rotation brings the bent end into the same direction as the continuation from the elbow where the straightening of the released rod will project the end far enough into the pipe to insure the easy passage of the rod.

In withdrawing the device, the rotation is continued so that if one of the spaced coils of the bent end catches on an edge of the pipe sections it will be freed. The rotation also assists in loosening the grease etc., adhering to the walls of pipe.

Household drains are in a great majority of cases clogged within or near enough to the trap of the sink or other fixture to be reached with a flexible rod of the length mentioned above, and as the clogged material usually consists of soap, lint and other small particles which, if loosened will pass on into the sewer, a prompt use by the house-

holder of my improved implement will completely relieve the trouble without necessitating a call from the plumber or any disconnection of the pipes.

I claim:

1. An implement of the class described comprising a flexible rod formed by coiling a resilient wire in such manner that the turns in the coil are held in close contact by the tension of the wire, said rod being provided with a handle at one end whereby it may be grasped for facilitating a simultaneous thrust and rotation of the rod, and having at its opposite end a short permanently offset rigid portion bent at an angle to the axis of the coil with the turns thereof spaced apart.

2. An implement of the class described comprising a flexible rod formed by coiling a resilient wire into a coil having an internal diameter not substantially greater than the diameter of the wire, the turns of the coil being in close contact throughout substantially the entire length of the rod, a handle fixed to said rod at one end, said rod having at its opposite end a short permanently offset rigid portion bent at an angle to the axis of the coils with several turns of the wire between the bend and the end of the offset portion spaced apart, said rod having its extreme end free of any penetrating projection which would cause the end of the rod to work into the soft metal of a pipe upon rotation of the rod.

Signed at Maspeth, in the county of Queens and State of New York, this 5th day of Nov., 1915.

JAY H. WOOLHISER.
